UNITED STATES PATENT OFFICE.

JOHN J. REINHOLD, OF MARIETTA, PENNSYLVANIA.

PHONOGRAPH TURNTABLE.

Application filed April 6, 1922. Serial No. 550,237.

To all whom it may concern:

Be it known that I, JOHN J. REINHOLD, a citizen of the United States, residing at Marietta, in the county of Lancaster and State of Pennsylvania, have invented new and useful Improvements in Phonograph Turntables, of which the following is a specification.

This invention relates to phonograph 10 turn-tables and has for its object to provide a simple, cheap and durable device for guiding or centering phonograph records while they are being placed upon the turntable.

A further object is to provide a device of 15 this character which is applicable to records of different diameter.

This invention will be more fully understood from the following description, taken in connection with the accompanying drawings, 20 forming a part hereof, and in which similar numerals refer to similar parts throughout the several views.

Fig. 1, is a plan view of a phonograph turntable showing a practical embodiment 25 of this invention.

Fig. 2, is a sectional view of Fig. 1 taken on line 2—2.

In the drawing, the turntable 4 is mounted on the rotatable spindle 5 which extends 30 above the turntable forming a center pin 6. Carried by the base board 7 is a block 8 curved to fit around the turntable as shown. A plate 9 is secured to the outside surface 35 of the block 8 through studs 10 and nuts 11, and is provided with turned over ends 12. The plate 9 may be raised or lowered through the slot 14 to vary the space between the turned over ends 12 and the top surface of the block 8.

40 The construction shown in the drawing accommodates two sizes of records as indicated at 15 and 16. The top surface of the block 8 is slightly lower than the top surface of the turntable, thereby providing clearance for the large size record 16 as indicated at 17. The radius of the curved block 8 is slightly larger than the radius of the small size record 15 as indicated at 18. A portion of the turntable is cut away at 45 two places as indicated at 19.

When placing the small record on the turntable the same is placed in the position indicated at 20 in light broken lines Fig. 2, the edge butting against the block 8 as shown 50 at 21. The hole 22 of the record is then naturally over the center pin 6 and by re-

leasing the record at the point 23 the center pin will readily enter the hole in the record as the same falls to the table. It is apparent that the object of cutting a portion of 60 the turntable away as indicated at 19 is to make it possible to butt the edge of the record against the block 8, but it also serves an additional purpose in that the record can readily be gripped by the fingers when removing it from the table; this gripping of course taking place at the side of the table opposite to the block 8, hence the object of cutting a portion of the table away at two 65 places.

When placing the large size record on the table, the edge thereof is placed against the curved plate 9 at 24, which naturally brings the hole of this record directly over the center pin 6, similar to that described for the 75 small record, and in the same manner the center pin 6 enters the hole in the record when it is released to fall upon the table.

On account of the large size record being 80 larger than the turntable there is a possibility of the record tipping off the center pin, if through lack of care excessive pressure is brought upon the record in the direction, and at the point indicated by the arrow 25. To avoid an occurrence of this 85 kind the turned over ends 12 are provided, and the plate 9 is adjustable vertically so that the space between the turned over ends 12 and the top surface of the block 8 may be adjusted to accommodate records of different thickness.

To assure that the turntable always stops at the right position to cooperate with the curved block 8, I provide a positive stopping device in which, 26 is a lever pivoted 95 to the base board 7 through the screw 27. Forming part of the lever 26 is a sleeve 28 into which is fitted free to slide a hooked shaped rod 29. A spring 30 normally holds the hooked shaped rod 29 in the direction 100 indicated by the arrow 31 with the set collar 32 bearing against the end 33 of the sleeve. Screws 34 limit the turning movement of the lever 26 and also carry the lever guide plate 35.

Stop pins 36 are fixed in any suitable manner to the under side of the turn table as shown, and are adapted to engage with the hooked shaped rod 29 when the lever 26 is in the position shown in Fig. 1, (full lines).

The turntable rotating in the direction indicated by the arrow 37 continues to turn

until either of the pins 36 engage with the hooked shaped rod 29. The rod 29 being free to slide is yielding in its movement against the action of the spring 30; this affords an easy and positive stop for the turntable and assures that at all times either of the cut away portions of the turntable are in proper position relative to the block 8. When the lever 26 is moved to the position shown in light broken lines, the hooked shaped rod 29 is released from the pin 36 and the turn table is free to rotate.

Having thus described my invention, what I claim and desire to secure by United States Letters Patent is as follows:

15. 1. In combination with a phonograph turn-table, a center pin on the turn-table, and a gauge fixed stationary near the rim of said turn-table and adapted to guide a record to engage with said pin.
20. 2. In a phonograph record centering device, the combination with a rotatable table, of a center pin on said table, a record supporting member fixed near the rim of said table, said member being slightly lower than the table, and a gauge extending above said record supporting member and adapted to guide a record to engage with said center pin.
25. 3. In a phonograph record centering device, the combination with a rotatable table, of a center pin on said table, a record supporting member fixed near the rim of said

table and adapted to serve as a gauge to guide a record of small diameter to engage with said center pin, said record supporting member being slightly lower than said table, and a gauge extending above said record supporting member and adapted to guide a record of large diameter to engage with said center pin.

4. In combination with a phonograph turn-table, a center pin on the turn-table, a stationary gauge located relative to said center pin to guide a record to engage therewith, and means for preventing said record from tipping and disengage with said center pin.

5. In a phonograph record centering device, the combination with a gauge for centering the record, of a rotatable table the top surface of which being slightly higher than said gauge, said table having a portion of its rim cut away to permit engagement of said record with said gauge.

6. In a phonograph record centering device, comprising a record supporting member having substantially a flat top surface and curve shape sides, said curve shape sides forming a true arc around a common center, and a gauge fixed to the outer curve shape side and extending above said flat top surface.

In testimony whereof I hereby affix my signature.

JOHN J. REINHOLD.
